UNITED STATES PATENT OFFICE.

NEIL P. LEARY, OF WASHINGTON, DISTRICT OF COLUMBIA.

COMPUTER FOR ASCERTAINING TRANSPORTATION CHARGES.

1,120,948.

Specification of Letters Patent. Patented Dec. 15, 1914.

Application filed June 19, 1914. Serial No. 846,024.

To all whom it may concern:

Be it known that I, NEIL P. LEARY, a citizen of the United States, residing in Washington, District of Columbia, have invented 5 certain new and useful Improvements in Computers for Ascertaining Transportation Charges, of which the following is a specification.

The present method commonly employed 10 by transportation companies for ascertaining transportation charges on shipments is to refer to certain books, or pamphlets containing alphabetically arranged names of the various offices, from these obtain reference to certain tables giving the rates, and 15 having found the proper rate table and knowing the weight, select from a separate table of charges the desired charge, or multiply the weight by the rate to ascertain the transportation charge. At present, for instance, express companies have 294 different rates requiring 294 different tables, and 20 these rates are divided into two classes,—first and second. In addition to these, there are numerous publications of special rates 25 on commodities, etc. The turning of the pages to find the proper tables, the selection of the proper charge from the table and the calculation to obtain the desired transportation charge involves considerable labor 30 and time and often results in mistakes, due either to consulting the wrong rate table, the failure to select the proper charge, or to mistakes in calculation. Errors amounting to thousands of dollars in over charges 35 and under charges commonly occur each year involving not only losses to the transportation companies, and patrons, in violation of Federal statutes and abnormal action, but also great annoyance, and recurring complaints against the companies.

To reduce to a minimum errors of this kind, and to provide means for quickly ascertaining all transportation charges accurately without resorting to calculations, I have produced an apparatus which comprises a carefully prepared chart in the form of a tape divided into tables containing all, 45 or a selected portion, of the different charges in use. This table-carrying tape is wound on spools and is contained within a casing having an observation opening adapted to dis-

play a selected portion of one table of charges at a time, and in connection with 55 the table-display opening I employ a slide also having a relatively small observation opening, and this is adapted to select from the selected rate table the proper transportation charge for any desired weight or 60 standard package. Two tape spools are employed and these are operated by a hand wheel which is connected with the spools by gearing and pawl and ratchet mechanism so organized that when the wheel is turned in 65 one direction, one only of the spools is turned to wind the tape, and when turned in the opposite direction the other spool is operated to wind the tape, while the first designated spool runs free and permits the 70 tape to be unwound therefrom. The construction is such that the tape may, when desired, be moved at high speed and very quickly bring to view the proper rate table, and then knowing the weight or standard 75 package of the shipment the transportation charge for such shipment to its destination can be quickly ascertained by moving the slide to a position over the properly designated weight or standard package, indicated 80 on the selected table.

It will be understood therefore that the invention involves; first, a chart containing tables for the selected rates, these tables being carefully calculated and made permanent and requiring no calculations on the part of the user of the apparatus; second, means for bringing to an observation point the required table by easily operated and quick acting mechanism; and third, a device for selecting from the selected table the transportation charge for the shipment.

My improvements are illustrated in the accompanying drawings, in which,

Figure 1 is a perspective view of an apparatus for ascertaining transportation charges, embodying my invention. Fig. 2 is a detail view, with parts broken away, of a sample chart containing certain rate tables. Fig. 3 shows a vertical central section of the 100 apparatus on the line 3—3 of Fig. 1. Fig. 4 shows a horizontal section thereof on the line 4—4 of Fig. 3. Fig. 5 is a detail view, in vertical section, on an enlarged scale, of part of the mechanism showing particularly 105 a sample tape or chart carrying rate tables,

the tape spools and guide rollers and the observation opening in the top of the casing. Fig. 5^a is a detail view of the slide. Fig. 6 is a detail view, in vertical section, showing 5 parts of the mechanism for actuating the tape spools. Fig. 7 shows a vertical section on the line 7—7 of Fig. 6.

The frame of the apparatus may be of any suitable form and construction, but 10 preferably it consists of a casting having a skeleton bottom or base, comprising the bottom ring *a* and the cross pieces *a'*; cylindrical sides *b* having openings at *b'*, *b''* and a top ring *C*. These parts may all be made 15 by a single casting and the bottom of the frame may be covered by a sheet metal plate *a''*, detachably secured in place by screws *a''*. The openings *b'*, *b''* may be covered by sheet metal plates *B*, *B'*, held in place by screws 20 *b''*. The frame is of general cylindrical shape, but as shown has on one side a lateral extension *A* to accommodate certain gearing heretofore referred to.

Within the casing are mounted two spools 25 *D*, *E*, which support a chart *F* in the form of a tape having displayed thereon a series of rate tables, for instance, of the kind shown in Fig. 2. This tape is preferably made of cloth or other suitable material and 30 in practice is about thirty-six feet in length, although the length may vary within wide limits, and a little over twelve inches wide, but the width may vary. The tape spools *D*, *E* are supported by two brackets *G* (Fig. 35 5) connected as shown in Figs. 3 and 5 to angle bars *H* which have a sliding connection with angle bars *H'* attached to the base of the frame. The spools are suitably spaced and the tape passes upwardly from 40 the rolls and over guide rollers *I*, mounted in open bearings *i* at the top of the brackets *G*. The brackets are cast with recesses *g* which receive cylindrical bushings *g'* in which the pivots *d*, *e* of the spools *D* and *E* 45 have their bearings. These bushings are held in place by split pins *g''* and may be easily lifted out when desired. Ball bearings are preferably employed, but as these may be of any desired construction they are 50 not illustrated.

The top ring *C* of the frame is formed with a flange *c* on which rests the peripheral flange *m* of the top plate *M* and this plate is held in place by a ring *N*, secured to the ring 55 *C* by screws *n*. The plate *M* is slightly dished, as shown, and it is formed with an observation opening *M'* covered by a plate of glass *O* held in place by a rectangular frame *O'* resting on metal strips *o* secured to 60 the top plate *M*. A slide *P* having an observation opening *p* is mounted on the frame *O'* and may be moved back and forth thereon. It is held in place on said frame by springs *p'* which extend under the edges of

the frame. The slide is marked to indicate 65 lbs. and 1st and 2nd class rates, or made to indicate other measures of quantity and appropriate rates or charges.

Q indicates a hand wheel for operating the mechanism. It is of large diameter and 70 is preferably horizontally arranged on the top of the apparatus within convenient reach of the operator when using the device. The grip portion *q* of the wheel is rounded so as to be easily grasped and it is formed 75 with a laterally projecting annular portion *q'* which rests on anti-friction balls *q''* in a race-way formed in the ring *C*. The hand wheel is held in place by the ring *N* and by two detachable semi-annular plates *R*, secured 80 to the top ring *C* in the manner shown in Figs. 1 and 3. The flange *q'* is formed with a peripheral series of teeth which engage a pinion *s* on the vertical shaft *S*, mounted in bearings in the extension *A* of 85 the frame and carrying a pinion *s'* engaging another pinion *s''* on a horizontally arranged shaft *S'* mounted in bearings midway between the axes of the spools *D* and *E*. Preferably the shaft has its bearings in 90 cylindrical bearing blocks *t*, mounted in the brackets *T*. These blocks may be provided with ball bearings of usual construction.

To the shaft *S'* is secured a pawl-carrying wheel *U* of cylindrical form provided with 95 pins or pawls *u* which are pressed radially outward by springs *u'*. The wheel *U* is surrounded by two spur wheels *V*, *V'*, one of which, *V*, engages a pinion *v* on the spool *E* and the other of which, *V'*, engages a 100 pinion *v'* on the spool *D*. The wheels, *V*, *V'*, are arranged side by side and are independently movable. When the shaft *S'* is turned in one direction only the wheel *V* is turned and when the shaft *S'* is turned in 105 the opposite direction the wheel *V'* alone is operated. This is effected by forming in each wheel recesses *w* and corresponding shoulders *w'* oppositely arranged in such manner that when the wheel *U* is turned in one direction the pawls will engage the shoulders and turn the wheel which surrounds them, but when the shaft is turned in the opposite direction the pawls are depressed or moved radially inward and the surrounding wheel remains stationary. As 110 clearly shown in Fig. 6 there is a set of pawls for each of the wheels *V*, *V'* and the two sets of pawls are arranged side by side. 115

The chart or tape *F* is of sufficient length 120 to display the requisite number of rate scales or tables. The opposite ends of the tape are secured to the spools *D* and *E* and the tape is guided across the rollers *I* beneath the observation opening in the manner herein- 125 after explained.

The chart is made to display, in the present instance, 294 different rate tables and

each table is divided into two parts, one covering weights 1 to 50 lbs., the other 51 to 100 lbs. These are consecutively numbered, as indicated, and each part of each table is 5 preferably divided into three parts or columns, the two outer columns being numbered 1st—2d, to indicate first and second class charges and the middle column being headed lbs. to indicate weight. This last 10 mentioned column contains a series of numbers to indicate different numbers of pounds, hundredweight or the like. The outer columns contain designations of the charges for each number of pounds for both 15 first and second class shipments.

The apparatus is operated entirely by the manipulation of the hand wheel Q and the slide P. By turning the wheel Q in the proper direction the desired rate table may 20 be brought to view at the observation opening M' and because of the large diameter of the wheel Q and the small size of the pinion s the tape may be very rapidly operated if desired. If desired the wheel Q may be operated by power. The shipment is of course 25 first weighed and the place of destination being known the proper rate table if not already known is found from a suitable list and then the wheel Q is operated to bring 30 the desired table to view. Then the slide P is moved until the number indicating the weight is displayed through the opening p and then the transportation charge for both 35 first and second classes is shown on opposite sides of the weight number.

It will thus be seen that by my improvements the handling or turning of various sheets or pages and the usual calculations to ascertain rates, charges, etc. are avoided. 40 In my invention the calculations are all accurately made in advance and are permanent, and it is only necessary to operate the hand wheel, bring the proper rate table to view and to move the slide to the proper 45 point to show the charges on any desired weight, or standard package.

So far as I am aware I am the first to provide an apparatus for thus rapidly and accurately ascertaining transportation 50 charges and while I have shown an efficient way of embodying my invention I wish it to be understood that I do not limit myself to the apparatus shown and described, as variations therefrom may be made without departing from the novel features of my invention.

It will be observed that in the apparatus shown the parts are so constructed that they may be easily assembled or taken apart, and 60 any parts that are broken or worn out may be readily replaced. The tape-carrying spools D and E, it will be understood, are mounted in the brackets G which are secured to the metal strips H, in turn de-

tachably connected with the base of the 65 frame. The angle bars H' are fastened to the base of the frame while the bars H have a sliding connection with the angle bars as clearly illustrated. This connection is close so that there is no tendency for the brackets 70 to move out of place accidentally but when it is desired to remove the brackets, spools and tape it can be done by merely taking off the cover plate B and sliding the brackets, spools, etc. bodily out of the frame. By removing the cover plate B' the gearing between the hand wheel and the tape spool operating mechanism may also be reached with ease and the hand wheel and top plate of the apparatus are also made detachable and 75 readily replaceable. When the tape is moved to bring to view the selected rate table the entire table is visible and the rates for any number of pounds in this table may be seen, but there is always danger of mistake in inspecting a table in this way and selecting a rate, and in order to avoid any possibility of error the slide P is employed, the opening in which is just sufficient to expose a single designation for the weight and 80 single designations for the charges on same. In this way any possibility of error is avoided. The tape rolls and tape being readily removable, the tape may be easily removed and replaced by another tape of a different 85 design or of different arrangement if at any time required.

I claim as my invention:

1. An apparatus for ascertaining transportation charges, comprising a casing having an observation opening, a chart adapted to move beneath said observation opening, a chart mounting within the casing, a hand-wheel surrounding the observation opening and supported on the casing, and gearing 100 connecting the hand-wheel with the chart mounting for moving the chart.

2. An apparatus for ascertaining transportation charges, comprising a casing having an observation opening, a chart containing a series of rate tables adapted to move within the casing beneath said observation opening, a chart mounting within the casing on which the chart is supported, a hand-wheel having a peripheral series of teeth supported on the casing and surrounding the observation opening, and gearing 105 connecting the hand-wheel with the chart mounting for moving the chart.

3. An apparatus for ascertaining transportation charges, comprising a casing provided with an annular top rim, a top plate secured at its edges to the top rim and having an elongated observation opening, a chart mounted within the casing and adapted to move beneath said observation opening, a hand-wheel supported by the top rim and having an annular series of teeth, and 120 125

gearing operated by the hand-wheel for moving the chart.

4. An apparatus for ascertaining transportation charges, comprising a casing having a top rim and a lateral extension on one side, a chart mounting within the casing, a toothed hand-wheel supported on the top rim, and gearing within the lateral exten-

sion of the casing connecting the chart mounting with the hand-wheel. 10

In testimony whereof, I have hereunto subscribed my name.

NEIL P. LEARY.
